UNITED STATES PATENT OFFICE

161,055

ELECTRIC RANGE BACKSPLASHER

Ray C. Sandin, Oak Park, Ill., assignor to Hot-point Inc., a corporation of New York

Application December 7, 1949, Serial No. 6,489

Term of patent 14 years

(Cl. D81—25)

To all whom it may concern:

Be it known that I, Ray C. Sandin, a citizen of the United States, residing at Oak Park, in the county of Cook and State of Illinois, have invented a new, original, and ornamental Design for an Electric Range Backsplasher, of which the following is a specification, reference being had to the accompanying drawing, forming a part thereof.

In the drawing:

Figure 1 is a front perspective view of an electric range backsplasher, showing my new design; and

Fig. 2 is an enlarged vertical sectional view thereof, taken in the direction of the arrows along the line 2—2 in Fig. 1.

The dominant features of my design reside in the portions shown in full lines.

I claim:

The ornamental design for an electric range backsplasher, as shown.

RAY C. SANDIN.
